UNITED STATES PATENT OFFICE.

DAVID PRINCE, OF NEW YORK, N. Y., ASSIGNOR TO JACOB S. COHEN AND ISAAC S. COHEN, BOTH OF SAME PLACE.

FUR CAPE AND WAIST.

SPECIFICATION forming part of Letters Patent No. 286,959, dated October 16, 1883.

Application filed August 14, 1883. (No model.)

To all whom it may concern:

Be it known that I, DAVID PRINCE, a citizen of the United States, residing at New York, in the county of New York and State of New York, have invented certain new and useful Improvements in a Fur Cape and Waist; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention, and is a perspective view, taken in front. Fig. 2 is a perspective view of the back. Fig. 3 is a pattern of one-half of the garment. Fig. 4 is a view of one side of the design with the seam sewed up.

This invention has relation to a combined cape and waist; and it consists in the construction and novel arrangement of parts, as will be hereinafter fully described, and particularly pointed out in the claims appended.

In the accompanying drawings, *a* designates the back of the cape, which may be cut round or pointed. It terminates in a free edge, *b*, which is designed to extend downward as far as the upper edge, *c*, of the back portion of the waist or skirt *d*. In front the cape portion *e* and skirt portion *f* are connected by the front waist portions, *g*. These waist portions *g* do not extend around the back, their rear edges, *h*, being continuous above with the lower edge, *b*, of the cape, and below with the upper edge, *c*, of the back skirt, *d*. The edges *h* of the garment meet in front, and are con-

nected by suitable loops and buttons or other fastenings from the collar portion *m* downward to the lower edge, *n*, of the skirt. In this manner the garment is connected from the front portion of the cape to the front portion of the skirt by the waist-fronts only, the back being open, as at *z*, between the cape and back skirt. In front the garment has the appearance of a close-fitting sacque.

This garment may be manufactured of any other material without using fur, if desired; but it is usually made of fur, and suitably lined, and is intended for ladies' wear. The cape portion has two seams, *i i*, in each shoulder, and a middle back seam *k*. The back skirt has a middle back seam *l* and the waist-fronts have dart-seams *o o*.

Having thus fully described my invention, what I claim as new, and desire to secure by Letters Patent, is—

1. The combined fur waist and fur cape, consisting of the cape portion above and the skirt portion below, connected by the waist-fronts only, substantially as specified.

2. A combined cape and waist having the shoulder-seams *i i* in each shoulder of the cape portion, and the middle back seams *k* therein, the middle back seam *l* in the skirt portion, and the dart-seams *o o* in the waist-fronts, the cape and waist portions being disconnected at the back, substantially as specified.

In testimony whereof I affix my signature in presence of two witnesses.

DAVID PRINCE.
